ROLL PREVENTIVE DEVICE FOR A PENCIL OR THE LIKE

Alex E. Lookholder, 4928 Ledge Ave.,
North Hollywood, Calif. 91601

Filed Nov. 18, 1968, Ser. No. 14,516

Term of patent 14 years

Int. Cl. D19—

U.S. Cl. D74—13

FIG. 1

FIG. 2

FIG. 3

FIG. 4

FIG. 1 is a front perspective view of a roll preventive device for a pencil or the like showing my new design.

FIG. 2 is an elevational side view of the device.

FIGS. 3 and 4 are top and bottom views, respectively, of the device.

I claim:

The ornamental design for a roll preventive device for a pencil or the like, substantially as shown.
